UNITED STATES PATENT OFFICE.

THOMAS WILSON, JR., OF WATERVLIET, NEW YORK.

STORE-SERVICE APPARATUS.

SPECIFICATION forming part of Letters Patent No. 413,991, dated October 29, 1889.

Application filed May 17, 1889. Serial No. 311,202. (No model.)

To all whom it may concern:

Be it known that I, THOMAS WILSON, Jr., of Menard's, town of Watervliet, county of Albany, and State of New York, have invented 5 a new and useful Improvement in Store-Serv-ice Apparatus, of which the following is a specification.

My invention relates to a store-service app-
aratus in which a car or carrier is mounted
10 on a single wire constituting a track there-
for, said wire being secured at its ends to
vertically movable supports, by means of
which the wire track can be inclined in either
direction, the carrier being moved by gravity
15 when the wire track is so inclined.

My invention lies in the improvements
hereinafter described; and it consists of the
combination of devices hereinafter specified,
and especially pointed out in the claims.

20 Accompanying this specification and form-
ing a part of it is one plate of drawings, con-
taining five (5) figures, illustrating my inven-
tion, in all of which similar letters refer to
corresponding parts.

25 Figure 1 is a view in elevation showing my
improved apparatus arranged for operation,
the respective inclinations of the wire track
being shown in differently-arranged dotted
lines. Fig. 2 shows the device at one end of
30 my apparatus enlarged, with part of the tubu-
lar support therefor broken away to show de-
tails of construction, the carrier being engaged
with the catch. The tube is also broken at
35 about its middle transversely to allow for in-
definite length. The arrows indicate the di-
rection of motion of the operating parts. Fig.
3 is a horizontal section taken on the line 11
of Fig. 2. Fig. 4 shows a portion of the tube,
40 looking from the direction of the wire. Fig.
5 shows the metallic strip or shoe at the bot-
tom of the tube.

Fig. 1 illustrates a complete apparatus; but
for the purpose of elucidation a description
45 of the construction of the devices at one end
of the apparatus with its component parts
will suffice, as the two ends are similarly con-
structed.

A is a tube dependent from and fastened
to the ceiling X. The wire track R, on which
50 moves the carrier B, having the receptacle C,
terminates in the spring K, which spring is

attached at its other end to the pin P, which
in turn is fastened to the yoke Y. The ends
of this yoke expand into the arms Y' Y², the
wheels W' W² being adjusted between the 55
same and pivoted thereto, said wheels being
grooved to fit the curve of A vertically. (See
Figs. 2 and 3.) The bow of the yoke is pro-
vided with the lug y, to which is fastened the
line E. This line, moving in the direction of 60
arrow 1, passes up and over the wheel W,
which is pivoted in the tube A at its top, and
is carried down through the curved tubular
guide M, which is joined to the tube A by the
arm m, and serves to hold the line free of the 65
yoke and the wheels W' W².

At the bottom of the tube A is the shoe D,
fastened to the cap A', covering the free end
of the tube by the screw N. The shoe is com-
posed, preferably, of a single strip of flat 70
steel formed with the claw d³ at one end, and
having the other end bent upward and for-
ward and then turned sharply back on itself
to form the catch d'. The tube A is slotted
vertically and oppositely at T T, as well as 75
above where the wheel W is accommodated,
and is provided with the spring S, which rests
upon the inner face of the cap A', and ex-
tends up and a little above the lower end of
the slots T T, and with the spring S', which 80
depends from the pin or fastening s and ex-
tends a little below the upper ends of T T.
The pin P, to which the spring K, terminat-
ing the wire track R, is fastened, and which
in turn is fastened to the yoke Y, passes 85
through the bow of the yoke and through the
oppositely-placed slots T T, resting on the
spring S, and projects just beyond the cir-
cumference of the tube A and between the
arms Y' Y². (See Fig. 3.) 90

The car or carrier B is composed of two cor-
responding plates placed opposite one an-
other and solidly joined at b, b', and b², and
the wheels V V, adapted to revolve between
the two plates pivoted thereto and grooved 95
to fit the wire track R. At b³ b³ there are
openings between said plates on a line with
the grooves in the wheels V V, through which
the wire track R and spring K pass, serving
thereby to steady the carrier and car when 100
in transit. The receptacle C depends from
the carrier B by the arms c c, of which there

are four, two on either side of B, and running to opposite sides of C.

In operating my apparatus it should be borne in mind that each dependent tube with its appurtenances constitutes a station. In order to transmit the carrier B and its dependent receptacle C from one station, the handle e^2 of the line E is drawn in the direction indicated by arrow 2. This causes the yoke Y and the attached pin P, carrying the spring K and wire R, to move vertically in the direction of arrow 1, the said pin moving in the slotted guides T T. This movement continues until the pin P has reached, first, the spring S', and then, compressing that, the top of the slots, and is arrested by the solid tube. The line E is provided with a button e' , so adjusted with reference to its position on the line that when the pin P reaches the top of the slots e' shall be just below D. Then, if it is desired to retain the yoke and its attachments in the elevated position, the line E is slipped into the claw d^2 , and the button e' , resting against the bottom of D, holds it stationary. The position thus attained is shown by the dotted lines in Fig. 1. The act of raising the yoke and attached wire track R has disengaged the carrier at b from the catch d' , and the carrier and car are at once free to move along R with the impetus which their weight and the inclination of the wire track give to them. The spring K allows for the increased tension of R in moving to the position indicated by the dotted lines. As has been said, slipping the line E into the claw d^2 and the button e' under D holds the yoke and wire in their elevated position. If it is desired to return them to their normal position, (indicated by the continuous black lines, Fig. 1,) a slight additional pull of e^2 in the direction of arrow 2 enables e' to be released, and at the same time compresses S' to an extent that when the hold on the handle is loosened the recoil of S' and the weight of Y and its accompanying parts send the yoke, pin, and attached wire back to the bottom of the slots, where the pin P first strikes upon S, which acts as a cushion or buffer. The carrier and car moving on the inclined wire in the direction indicated by arrow 3 reach the other station, constructed precisely as the station they have just left, where the end b of the carrier is caught and retained by the catch d' , formed at the end of the shoe D. To return the carrier and car to the first station the same movements are made use of as have already been described, giving a position and

incline indicated by the dotted and broken line R².

I am aware that tracks have been heretofore constructed in which either end can be raised by vertically-movable end supports, so as to form an incline; hence I do not claim, broadly, a track adapted to be so manipulated.

Having thus described my invention, what I seek to secure by Letters Patent is—

1. In a store-service apparatus, the combination of the vertically - depending tube formed with oppositely - arranged vertical guide-slots, a sliding yoke arranged on the tube, friction-rollers journaled in the yoke to bear on the face of the tube, a track-supporting pin arranged in the sliding yoke and through the slots of the tube, and mechanism for lifting the sliding yoke and track-supporting pin, substantially as described.

2. In a store-service apparatus, the combination of a vertically-depending tube formed with oppositely-arranged vertical slots, a sliding yoke arranged on the tube, provided with friction-wheels to bear against the face of the tube, a track - supporting pin extending through the sliding yoke and through the slots of the tube, mechanism to lift the sliding yoke and track-support, and elastic cushions interiorly arranged in the top and bottom of the tube to contact the track-supporting pin, substantially as and for the purpose specified.

3. In a store-service apparatus, the combination of the vertically-depending tube having oppositely-arranged vertical slots, a sliding yoke on the exterior of the tube, a track-holding pin in the yoke and extending through the slots of the tube, a wire track, and an extensible spring-connection supporting the end of the track and fixed to the end of the track-holding pin, substantially as and for the purpose specified.

4. In a store-service apparatus, a dependent oppositely-slotted tube, such as described, combined with a vertically-movable yoke and a mechanism for producing such movements, and provided with the shoe D, formed with the catch d' and the claw d^2 , as hereinbefore described and set forth.

In witness whereof I have hereunto set my hand this 14th day of May, in the year of our Lord 1889.

THOMAS WILSON, JR.

In presence of—

JAMES HACKETT,
JOHN F. CANNY.
